SCARF HOLDER AND FORMER

Filed May 4, 1927

Inventor.

George Hollafolla.

By Harry De Wallace.

Attorney.

UNITED STATES PATENT OFFICE.

GEORGE HOLLAFOLLA, OF SYRACUSE, NEW YORK.

SCARF HOLDER AND FORMER.

Application filed May 4, 1927. Serial No. 188,831.

This invention relates to means for forming and holding four-in-hand neck scarfs when worn with turn-down collars, and has for its object to provide novel construction and arrangement of the device, which consists of a single length of spring wire bent and coiled to provide a flexible open frame or form, around which the scarf may be folded and tied, and by means of which the scarf may be readily and quickly applied to and removed from the collar without untying the scarf, the said form being so arranged that a neat and permanent knot may be tied, and the scarf may be applied to the usual turn-down collar without requiring the medial portion of the scarf to be passed around the neck and between the more or less closely folded portions of the collar. A further object is to provide a spring metal form for four-in-hand neck scarfs which may be readily flexed to conform to collars of different shape, and may be also adjusted for disposing the knot in different positions relatively to the gap of the collar. And a further object is to provide means for holding the knot as well as the skirt of the scarf clear of the shirt bosom.

I attain these objects by the means set forth in the detailed description which follows, and as illustrated by the accompanying drawing, in which—

Figure 1 is a front elevation of the complete device. Fig. 2 is a top plan view of the same. Fig. 3 is an end elevation, showing the first step in applying the scarf to the form. Fig. 4 is a face view of the scarf, folded for the initial step of Fig. 3. Fig. 5 is a front elevation of the device of Fig. 3. And Fig. 6 is a front elevation, showing the scarf completely tied and ready to be applied to a collar.

In the drawing, a light gauge spring wire is folded and bent to form an open angular frame A, comprising similar oppositely inclined arms or wings, 2—2', the top and bottom margins 2^a—2^b being substantially parallel, and the bottom 2^b being formed medially with an inverted U-shaped bend 3, which is adapted to be hooked over a collar button (not shown). At the start of the construction of the frame, the loop 3 is usually formed about midway of the length of the wire, after which the portions 3'—3^a at the opposite sides of said bend are correspondingly bent upwardly, as at 3^b, and then inwardly, as at 3^c, which completes

the shaping of the frame A. At this stage, the free end portions 3'—3^a of the wire comprising the top 2^a are overlapped, and each strand is then coiled around the other in the same direction and to the same extent, as shown respectively at 4—4' in Figs. 1, 2 and 5, the portions 3'—3^a thence being extended downwardly convergently and providing a triangle, as 5. The strand 3' preferably continues downwardly and is folded upon itself to form a relatively long and broad loop, as 6 (see Figs. 1, 2, 3 and 5), from which said strand is carried upwardly across the triangle and is finally secured by coiling its end between the coils 4—4', which are suitably spaced for the purpose. The loose end of the strand 3^a is next wound in a coil 7 around the fold of strand 3' midway between the triangle 5 and the loop 6 for securely binding the parts. The triangular formation 5 tends to brace the loop 6 and prevents lateral distortion of the same. The loop 6 is preferably curved outwardly away from the bend 3, primarily for affording suitable clearance between the bottom 2^b of the frame and said loop, for convenience in applying and tying the scarf, as 8, shown in Fig. 3. To make the scarf 8 ready for application to the frame, the narrow medial portion 8' is preferably first folded upon itself, as shown in Fig. 4. This medial portion is then inserted upwardly between the bottom 2^b and the loop 6 and folded forwardly over the coils 4—4', and is thence inserted downwardly through the loop 6, as best seen in Figs. 3 and 5. The narrow top portion α of the longer end of the skirt 8^a of the scarf is next wound around the triangle 5 and loop 6, as well as around the fold 8', and the adjacent portion 8^b being the short end of the scarf, as shown at 8^c in Fig. 6. The free end of the skirt 8^a is next passed between the frame portions 2^a—2^b and folded forwardly as at 8^d and is finally inserted downwardly between the windings 8^e, as shown in Fig. 6, for completing the tying of the knot. After the narrow portion 8' of the tie is inserted through the loop 6, as in Fig. 3, the usual method of tying the ordinary four-in-hand ties may be followed, as explained. The main frame A is preferably flexible in all directions, so as to readily conform to turn-down collars of different size, shape and style. For relatively high collars, the vertical spread of the frame A should be, for example, as shown by the

full lines in Fig. 1, and when the holder is employed in connection with relatively narrow or low collars, the bottom 2^b may be flexed upwardly by the wearer, to the extent shown by the dotted lines in Fig. 1. The loop 6 and the triangle 5 preferably incline forwardly from the frame A, as explained, and this inclination is effected and maintained by winding the coils 4—4' in the direction and ending said coils as indicated in Figs. 1, 2 and 3. A particular object in curving the loop 6 forwardly (see Fig. 3), is to facilitate the insertion or threading of the fold 8', as well as to suitably space the knot and the upper portion of the skirt 8^a from the shirt bosom. A particular function of the triangular portion 5 is to space and brace the loop 6 for holding the pendant tie in proper position. When the scarf 8 is applied to the frame and suitably adjusted and tied, these two parts may be handled as one, and the scarf may be applied to the collar repeatedly by simply inserting the arms 2—2' between the folded ends of the collar and hooking the bend 3 over the collar button, without disturbing the assembly shown in Fig. 6, and without requiring separation or readjustment of said parts. To remove the scarf, the wearer lifts the bottom portion 2^b clear of the button and withdraws the frame A from the collar.

Having thus described my invention, what I claim, is—

1. In a scarf form, a normally open form comprising a single length of spring wire, the end portions of the wire overlapping at the top and midway between the ends of the form, said end portions being coiled around each other in separate coils, said end portions extending downwardly convergingly to form a triangle, one end portion being formed into a long loop below the tri-

angle and terminating in a single coil between the first coils, the other end portion being wound around the first end portion between the triangle and said loop, and the bottom of the form being formed with a medial bend to engage a collar button. 45

2. A scarf holder comprising a single length of spring wire bent intermediate its ends to form an open frame having inclined arms adapted to be inserted in the facing ends of a turn-down collar, the bottom of the frame having a bend to engage the collar button, the top of the frame comprising 50 the loose end portions of the wire, said portions being wound in spaced coils and converging forwardly and downwardly, one end portion being folded into a loop below the point of convergence and terminating between the spaced coils, and the other end portion being wound around the first end portion adjacent said loop. 55

3. In a scarf holder, an open resilient frame formed from a single wire, the medial portion of the wire having a bend to engage a collar button, said bend being disposed in the bottom of the frame and the wire at the opposite sides of said bend being bent upwardly and then inwardly to form the ends 60 and the top of the frame, the loose ends of the wire overlapping at the middle of the top and being coiled around each other in the same direction and to the same extent in spaced relation, the remaining portions 65 of the wire converging towards said bend, one of said portions being folded upon itself to provide a long loop that extends beyond said bend, and the other portion being coiled around the first portion between the 70 loop and said spaced coils. 75

In testimony whereof I affix my signature.

GEORGE HOLLAFOLLA.
